UNITED STATES PATENT OFFICE.

THOMAS SHIPLEY, OF YORK, PENNSYLVANIA.

HINGED DOOR.

Application filed June 1, 1923. Serial No. 642,798.

To all whom it may concern:

Be it known that I, THOMAS SHIPLEY, a citizen of the United States, residing at York, in the county of York and State of Pennsylvania, have invented certain new and useful Improvements in Hinged Doors, of which the following is a specification.

This invention relates to hinged doors and particularly to trap doors or hatch doors of the type in which a plurality of adjacent doors or door sections are hinged on substantially aligned horizontal axes.

As a secondary feature, the invention involves a series of such doors arranged so that each overlaps another in the series so that the doors must be opened and closed serially, and when closed offer a relatively tight closure.

I have successfully applied the invention in the refrigerating art as a part of the heat insulating structure of can ice plants. In a plant of the pusher type, for example, the brine tank is covered by a deck. The cans are inserted and filled at one end of the brine tank in successive transverse rows, and are thereafter advanced step by step toward the opposite end of the tank beneath the aforesaid insulating deck. The door structure about to be described is used to close the opening in the deck through which the cans are inserted.

While not limited in its utility thereto, the invention offers particular advantages in plants of this type because the opening is of considerable extent and because the doors are heat insulated and consequently quite heavy.

Such an embodiment of the invention is illustrated in the accompanying drawing in which:

Fig. 1 is a fragmentary plan view showing one door fully open and the second door partially open and ready to start the movement of the third door, which is closed;

Fig. 2 is a section on the line 2-2 of Fig. 1 and

Fig. 3 is a section on the line 3-3 of Fig. 1.

The deck which extends over the brine tank is indicated at 5 and the head wall which extends across the brine tank is indicated at 6. A transverse deck 7 extends across the head end of the brine tank at a level lower than the level of the deck 5. A sill 8 of somewhat greater height than

the thickness of the doors 9 extends along the margin of the deck 7. A jamb or sill 10 is carried by the margin of the deck 5 to support the outer edges of the doors 9.

The doors 9 are of any usual heat insulated construction and include generally a top sheathing 11 and a lower sheathing 12 both of wood spaced apart by a marginal frame 13 with the intervening space filled with cork or other insulation 14.

The top sheathing 11 is offset laterally so that along one edge of each door there is a projecting flange which lies in a corresponding recess in the adjacent edge of the next door. Similarly, the sheathing 11 projects beyond the frame 13 at the edge of the door opposite the hinges (see Fig. 2) to produce a flange which seats on the jamb 10. Each door is mounted on two strap hinges 15 whose axis is at the upper corner of the sill 8 and so arranged that the doors 9 swing from a horizontal closed position, in which they rest on the tops of the sill 8 and jamb 10, to an open position in which their outer ends rest on a filler strip 16 provided to afford the necessary clearance for the hinge straps and their connecting bolts.

Mounted on the under face of each door is an iron 17 which extends transversely of the door at a slightly oblique angle and projects beyond the margin of the door at that side which has the flange-receiving recess above described. This iron might be connected with the door in any suitable way but I prefer to connect it by means of an eye bolt 18 which extends through the door and through the strap of one of the hinges 15 and an ordinary bolt 19 which passes through the iron 17 and the other one of the hinges 15.

The projecting end of the iron 17 is formed with an eye 20, and a chain 21 connects the eye 20 of one door with the eye bolt 18 of the next door. Consequently, successive doors are connected by successive chains 21, the chains 21 serving as limit stops controlling the relative angular movement of successive doors.

The length of the chains 21 is such that as a door is swung from open toward closed position or from closed toward open position it will move slightly past its vertical position before the chain 21 tightens and commences to entrain the next succeeding door.

The effect of having the iron 17 project beyond the edge of its door is to cause the chain to draw in a straight line clear of the edges of the doors so that the doors are not 5 chafed by the chains.

The construction is such that the doors must be opened and closed in strict serial order. After the first door has been opened to the position at which its chain 21 draws 10 taut, the partially opened door as it completes its opening movement entrains the next door and serves as a counterweight to assist its opening movement. In this way each successive door acts as a counterbalance 15 for the next and the whole series of doors may be opened very rapidly and with minimum physical labor. They are closed in the reverse order and in their closing movements offer the same counterbalancing and 20 labor-saving effect. The counterbalancing action is dependent upon the use of a horizontal or approximately horizontal axis for the doors. Obviously it is not necessary that the doors be strictly horizontal in either 25 their open or closed positions, the essential condition being that in their swinging movements between open to closed positions they pass through a position in which the effect of gravity is neutral. In the example illustrated this neutral position is an approximately 30 vertical position. Hence, I do not limit myself to the specific arrangement shown nor to the specific field of use suggested. However, the very considerable 35 weight of heat insulated doors and the large size of the hatchways in can ice plants makes the structure a peculiarly desirable one in this field.

What is claimed is:

40 1. The combination of a plurality of doors hinged on substantially aligned axes, to swing from a closed position through ap-

proximately 180 degrees to an open position; of limit stop means engaging between adjacent doors and serving to cause the final 45 opening movement of one door to effect the initial opening movement of the next.

2. The combination of a plurality of doors hinged on substantially aligned horizontal axes to swing between open and closed positions on opposite sides of the vertical positions of the doors, of limit stop means between adjacent doors whereby the final movement of one door in one direction effects the initial movement of an adjacent 50 door in the same direction, the doors when moving simultaneously serving to counterbalance each other.

3. The combination of a plurality of doors hinged on substantially aligned horizontal axes to swing between open and closed positions on opposite sides of the vertical positions of the doors, and connecting chains extending from door to door and limiting their relative angular movement, whereby 55 each door draws a succeeding door after it and one door serves to counterbalance another.

4. The combination of a series of doors hinged on substantially aligned horizontal axes to swing between open and closed positions on opposite sides of the vertical position, each door of the series having a portion which overlaps the next, whereby 60 serial movement of the doors is imposed; and limit stop means acting between successive doors of the series, whereby the final motion of each successive door effects the simultaneous initial movement of another 65 door later in the series.

In testimony whereof I have signed my name to this specification.

THOMAS SHIPLEY.
